ATTORNEY

UNITED STATES PATENT OFFICE

DONALD M. MAY, OF ROCKY POINT, NEW YORK

PORTABLE TYPEWRITER ATTACHMENT

Application filed October 4, 1929. Serial No. 397,241.

My invention relates to typewriter attachments and it consists in the constructions, arrangements, and combinations herein described and claimed.

5 It is an object of my invention to provide an attachment for typewriters and other machines, whereby the carriages, (or moving part) can be returned to commence a new line and also rotate the platen for proper 10 spacing of the lines without the necessity for an operator to move his hands from position on the key-board.

15 It is a further object of the invention to provide an attachment for shifting the carriage of a typewriter by manipulation of a foot treadle.

20 It is a further object of my invention to provide an attachment for shifting the carriage of a typewriter which is portable and easily attached and detached to the typewriter or other machine which it is designed to operate.

25 It is a still further object to provide a carriage shift device which is readily applicable to any of the well known makes of typewriters without material alterations or readjustment of the parts.

30 Additional objects, advantages and features of invention will be apparent from the following description and accompanying drawings, wherein,

Figure 1 is a front elevation of a typewriter equipped with my invention,

35 Figure 2 is a vertical section on the line 2—2 of Fig. 1,

Figure 3 is a cross section on the line 3—3 of Fig. 1,

Figure 4 is a perspective view of the pulley and its mounting,

40 Figure 5 is a detail perspective view of the operating cable and its attaching fixture, and

Figure 6 is a detail view of a modified portion of the device.

45 In carrying out my invention I make use of any of the well known typewriters, generally indicated by the reference character 1, having a carriage shift and platen manipulating lever 2. Upon the typewriter 1, opposite the side carrying the lever 2 there is provided a cable-attaching plate 3, which may

be secured to the frame of the typewriter, as by screws or otherwise. The plate 3 has a bayonet slot 4 adapted to receive the winged portions 5 of a coupling 6. By this construction, it will be readily apparent that the coupling 6 may be quickly attached or detached from the plate 3 by giving the coupling 6 a partial turning movement.

55 The coupling 6 is hollow, and upon the end opposite the winged portions 5 a flexible and non-compressible tubing 7 is secured, through which there is extended a cable 8, one end of which is suitably secured to the lever 2.

A foot treadle 9 is provided and is mounted upon a base 10 having an upright yoke 11 to which one end of the tubing 7 is secured as at 12.

60 The treadle 9 is pivotally mounted upon the base 10, as at 13, and a helical spring 14 is positioned between the base 10 and treadle 9 to hold the treadle in its uppermost or operative position.

65 Upon the forward portion of the treadle 9, a substantially U-shaped frame 15 is secured, within which a pulley 16 is swingably or otherwise mounted.

70 Reference is now made to Figures 3 and 4, wherein it is clearly shown that the pulley 16 is rotatably supported within a housing 17. The housing 17 has trunnions 18 at opposite sides, journaled within the U-shaped frame 15.

75 Attention is now directed to Figures 2 and 3, wherein it will be seen that the pulley 16 is directly in line with the yoke 11 and therefore properly positioned to receive the cable 8. The cable 8 is entrained about the pulley 16, through an eyelet 19 and the terminal thereof finally secured upon the cleat 20 carried by the yoke 11. By providing the pulley 16 in the swingable housing 17, the cable 8 is properly retained within the pulley at all times regardless of the various positions which the treadle may assume when depressed by an operator.

80 85 90 95 100 Also, it should be noted that the tension of the cable 8 may be readily varied, by releasing the cable 8 at the cleat 20, to lengthen or shorten the cable, as the case may be. Ordinarily, one depression of the treadle 9 will

be sufficient to return the carriage 21 to its normal starting position.

My operating treadle and attached pulley may comprise various forms, one modification of which is shown in Figure 6, at 9^a. This treadle is equipped with a comfortable and efficient heel rest 9^b. In place of the U-shaped member 15, as used in the preferred form of my device, I fasten to the treadle 9^a 10 the angle brackets 15^b by screws or other suitable means. These angle brackets provide bearings for the roller used in this form of the device shown at 16^a. It is readily apparent that this form of my device may be 15 used in place of its equivalent member in the preferred form.

In operation, an operator having manipulated the typewriter so that the carriage 21 is at the extreme left, and it is desired to 20 rotate the platen and return the carriage to its initial starting point, the treadle 9 is rocked by the foot of an operator. Such rocking movement of the treadle will pull downwardly upon the cable 8 which in turn 25 pulls upon the lever 2. Movement of the lever 2 will rotate the platen and at the same time will draw the carriage 21 to the right, and into position to receive the next line of typing.

It is also apparent that the foot engaging portion of my device may be moved freely to any position desired by the operator, the flexible but not compressible tubing 7 which 30 may consist of metal coiled tubing or other 35 suitably formed tubing permitting this operation, while also due to its non-compressibility allowing free operation of the tension cord within. This tubing encasing the tension cord prevents any obstruction or 40 entanglement of said tension cord due to engagement with portions of the typewriter or other objects in its vicinity. It is also 45 easily seen that it can be readily transported, by simply detaching the flexible tubing 7 from the plate 3, to any other place and for use on any other machine, as desired.

From the foregoing, it will be seen that I 50 have provided a carriage return mechanism which is operable entirely by the foot of an operator, which will be liable in a minimum degree to derangement, and which is a portable attachment.

I claim:—

1. In a device of the character described, 55 a base, a foot treadle rockably mounted thereon, a rotatably mounted pulley thereon, an upright yoke carried by said base and disposed over said pulley, and a cable slid able through said yoke and about said pulley.

2. In a device of the character described, 60 a base, an upright yoke thereon, a rockably mounted foot treadle on said base, a rotatably mounted pulley carried by the free end of said treadle and disposed beneath said yoke,

and a pull cord slid able through said yoke and around said pulley.

3. In a device of the character described, 70 a base, an upright yoke thereon, a rockably mounted foot treadle on said base, a rotatably mounted pulley carried by the free end of said treadle and disposed beneath said yoke, a pull cord slid able through said yoke and around said pulley, and means for varying the length of said pull cord. 75

4. A device for operating carriages of type-writers and other machines and simultaneously line spacing, a lever carried by the carriage of the typewriter, a foot treadle, a yoke positioned above said foot treadle, a cable connected between said lever and said foot treadle through said yoke, a tubing connected to said yoke and detachably connected to a portion of the typewriter opposite said lever and encasing said cable, whereby upon 80 movement of said foot treadle said carriage will be operated. 85
